UNITED STATES PATENT OFFICE.

FRANCIS KARE, OF HOLLAND, MICHIGAN.

PILLOW.

Application filed December 4, 1928. Serial No. 152,579.

This invention relates to pillows and more particularly to pillows comprising a detachable resilient unit.

One of the objects of the invention is the provision of a new and improved pillow which may be assembled by a folding operation.

Another object of the invention is the provision of a new and improved pad having 10 wings attached thereto that may be folded in such a manner as to form a pillow.

A further object of the invention is the provision of a new and improved pad having wing extensions together with a resilient 15 unit about which the wing extensions are adapted to be folded.

A still further object of the invention is the provision of a foldable pad that is adapted to be employed as a pillow, with or 20 without a spring unit, that is simple in construction, cheap to manufacture, that may be readily folded to form a pillow, that may be reversed, and one that is neat in appearance, comfortable and durable.

Other and further objects and advantages 25 of the invention will appear from the following description taken in connection with the accompanying drawings, in which

Fig. 1 is a plan view of the pillow in position for use;

Fig. 2 is a cross-section on line 2—2 of Fig. 1, on an enlarged scale;

Fig. 3 is a plan view of the pillow in unfolded position;

Figs. 4 and 5 are plan views of the pillow 35 in partially folded position; and

Fig. 6 is a plan view of a portion of a spring unit showing the silencer in position therein.

In the fabrication of pillows it is desirable 40 that the parts be so constructed that they may be readily reversed in order to expose different surfaces.

It is also desirable that in the type of pillow 45 in which a resilient unit is employed the parts be so constructed that they form a comfortable pillow without the resilient unit.

The present invention seeks to produce a pillow that may be employed with or without 50 a resilient unit, and one that may be reversed when one side becomes soiled, or for other reasons it is necessary or desirable to expose other portions of the pillow.

In the form of the device selected to illustrate 55 one embodiment of the invention the reference character 10 designates generally

a pad having the body portion 11 which is adapted to be folded along the dotted lines 12, 13 and 14 as indicated in Fig. 3. For convenience in description the pad 10 will be considered as being divided by the dotted lines 12, 13 and 14 into the sections 15, 16, 17 and 18 respectively. In practice the pad 10 is preferably of the same thickness throughout its length.

The pad is provided with wings 19 and 21 arranged in staggered relation on the opposite side edges of the pad. As shown, the wing 19 is attached to the section 17 and the section 21 to the opposite edge of the adjacent section 16. These wings are preferably padded in the same manner as the pad 10.

Preferably, though not necessarily, a spring unit 19 is employed with the pad. The unit 19 may be of any suitable arrangement of springs. In the form shown, which is by the way of example only, a plurality of spiral springs 21 arranged in rows and having their terminal coils connected together by helicals 22, are employed. In order that the coils of the springs may not frictionally engage or come into contact with each other to make objectional noises, an elongated padding 23 is woven about the coils of the springs as shown in Fig. 6.

If desired, certain sections of the pad or its wings may be of different color from the remaining portion, or the sections may be of one color on one side and a different color on the other side, whereby different colors may be exposed as desired.

The pad and its wings may be folded in various ways. As shown in Figs. 3, 4 and 5 the spring unit 19, if one be employed, is placed on the section 16 and the wing 20 folded thereover, see Fig. 4. The whole is then folded onto the section 17 as shown in Fig. 5. The wing 19 is then folded onto the folded portion, after which the folding operation is completed by folding the section 18 over onto the folded mass. The same operation is performed when the spring unit is omitted.

If desired, the section 15 may be folded before the wing 20, or the folding may begin at the opposite end of the pad. In order to expose a clean surface or a different color the pad may be turned over and folded as before. The pad may be folded in numerous ways, which will readily occur to the person folding the same.

It is thought from the foregoing taken in

connection with the accompanying drawings that the construction and operation of my device will be apparent to those skilled in the art, and that various changes in size, shape, proportion and details of construction may be made without departing from the spirit and scope of the appended claims.

I claim as my invention:

1. In combination, a pad having a body portion provided with wings attached to opposite side edges of said pad in staggered relation, whereby said wings and body portion may be folded into a compact bundle to form a pillow.
- 15 2. In combination, a pad having a body portion provided with wings attached to opposite side edges of said pad in staggered relation, whereby said wings and body portion may be folded into a compact bundle to 20 form a pillow, and a resilient unit enveloped in the folds of said wings and body portion.
- 20 3. A resilient pillow comprising a resilient

unit, a padded body portion folded over and extending about both sides of said unit, and a wing portion secured to one side edge of 25 said body portion and folded over one side of said unit in a direction at an angle to the folding of said body portion.

4. A resilient pillow comprising a foldable, padded body portion, a resilient unit about 30 which said body portion is folded, and a padded wing portion attached to each side edge of said body portion and folded over the sides of said unit in a direction at right angles to the folding of said body portion. 35

5. In combination, a resilient unit, a cover for said unit, said cover comprising a body portion folded about said unit in one direction, wings attached to opposite side edges of said body portion in staggered relation, 40 and folded about said unit at right angles to said first-named direction.

In testimony whereof I affix my signature.
FRANCIS KARR.
